[57] CLAIM

The ornamental design of an illuminable door latch alarm, as shown and described.

DESCRIPTION

FIG. 1 is a front perspective view of an illuminable door latch alarm showing my new design; with the undisclosed rear being plain and unornamented;

FIG. 2 is a top plan view thereof, with the bottom being a mirror image;

FIG. 3 is a perspective view thereof, with the broken lines showing for illustrative purposes only and forming no part of the claimed design.

FIG. 1

FIG. 2

FIG. 3
